UNITED STATES PATENT OFFICE

129,406

DESIGN FOR AN ADVERTISING DISPLAY PLACARD OR THE LIKE

Henry C. Whittlesey, Gladwyne, Pa., assignor to Keasbey & Mattison Company, Ambler, Pa., a corporation of Pennsylvania

Application March 25, 1941, Serial No. 99,877

Term of patent 7 years

To all whom it may concern:

Be it known that I, Henry C. Whittlesey, a citizen of the United States, residing at Gladwyne, in the county of Montgomery and State of Pennsylvania, have invented a new, original, and ornamental Design for an Advertising Display Placard or the like, of which the following is a specification, reference being had to the accompanying drawing forming part thereof, in which:

Fig. 1 is a front elevational view of an advertising display placard, showing my new design; and

Fig. 2 is a side edge view.

I claim:

The ornamental design for an advertising display placard or the like, substantially as shown.

HENRY C. WHITTLESEY.
